UNITED STATES PATENT OFFICE

PAUL A. HENTSCHEL, OF BALTIMORE, MARYLAND

DESIGN FOR A FLUE DEFLECTOR FOR GAS STOVES

Application filed May 19, 1930. Serial No. 35,686. Term of patent 14 years.

To all whom it may concern:

Be it known that I, PAUL A. HENTSCHEL, a citizen of the United States, resident of Baltimore, in the State of Maryland, have invented a new, original, and ornamental Design for a Flue Deflector for Gas Stoves, of which the following is a specification, reference being had to the accompanying drawing, forming part thereof.

The figure is a perspective view of the deflector showing my new design.

The back side of the article opposite the perforated or ornamented front face is plain and imperforated while the right hand end face is of the same appearance as that shown on the left.

I claim:

The ornamental design for a flue deflector for gas stoves as shown and described.

PAUL A. HENTSCHEL.
